UNITED STATES PATENT OFFICE.

JOHN E. MACLACHLAN, OF BOSTON, MASSACHUSETTS.

LOOSE-LEAF BINDER.

No. 873,151.

Specification of Letters Patent.

Patented Dec. 10, 1907.

Application filed June 27, 1907. Serial No. 381,001.

To all whom it may concern:

Be it known that I, JOHN E. MACLACHLAN, a citizen of the United States, residing in Boston, in the county of Suffolk and State 5 of Massachusetts, have invented new and useful Improvements in Loose-Leaf Binders, of which the following is a specification.

This invention relates to a certain novel construction and arrangement of parts where- 10 by a loose-leaf binder is produced in which a plate or bar provided with one-half of a set of leaf-receiving posts is rigidly secured to the cover, and the other half of said set of leaf-receiving posts is rigidly secured 15 to a plate or bar which is pivotally connected at one end with the stationary plate or bar and is adapted to swing therefrom and open the posts for the purpose of removing the leaves, and to be returned to and locked in 20 position on and parallel with the stationary plate or bar, thus closing the opposite posts in the set for the purpose of retaining the leaves in the binder.

The nature of the invention is fully de- 25 scribed in detail below, and illustrated in the accompanying drawings, in which:-

Figure 1 represents a portion of a loose-leaf binder spread or laid open and embodying my invention—the leaf-receiving posts 30 being closed. Fig. 2 is a view in detail of the central portion of the cover with the posts swung open. Fig. 3 is a section taken on line 3—3, Fig. 1. Fig. 4 is a section taken on line 4—4, Fig. 1. Fig. 5 is a section taken 35 on line 5—5, Fig. 2.

Similar letters of reference indicate corresponding parts.

a, a represent the two sides of a cover, and *b* is the connecting back thereof. Riveted 40 or otherwise rigidly secured lengthwise to the back is the flat bar *d*. Pivotally secured at *e* to one end of the bar *d* is a swinging bar *g* similar in size and shape to the bar *d*.

h, h represent two curved posts of sub- 45 stantially the shape of one half of a circle, notched at their outer ends, said posts being rigidly secured to the bar *d*.

k, k represent two oppositely curved posts rigidly secured to the bar *g*, and adapted 50 when the posts are in a closed position, as shown in Figs. 1 and 4, to constitute (with the posts *h*) two complete closed posts for holding the leaves *s*. The posts in themselves considered are not new in this invention. 55

The bar *d*, which with its posts constitutes

the stationary member of the device, is pro- 60 vided with raised lips of reverse L-shape *l*, *m* and *n* formed up from the bar and with their horizontal portions facing the right 65 hand edge of said bar. A small protuber- 70 ance *o* is also formed up from the bar *d* near the end which is not pivotally connected with the bar *g*. The bar *g*, which with its 75 posts constitutes the swinging member of 80 the device, is provided at its inner edge with curved recesses *p* adapted when the device is closed to accommodate the posts *h*, and with three more recesses *q*, *r* and *t* in the same edge and of equal depth which register 85 respectively with the lips *l*, *m* and *n*. A curved slot *u* is formed near the hinged end of the bar *g*, and a pin *v* extends from the bar *d* into said slot.

When the device is closed, the swinging 75 bar or member *g* is directly over the stationary bar or member *d*, the pin *v* is at the extreme right end of the slot *u*, and the lips *l*, *m* and *n* overlap the bar *g* by extending over and beyond the ends of the recesses *q*, *r* and *t* 80 respectively. When the bars are in this position they are locked by friction by means of the protuberance *o* which presses against the under side of the bar *g*. When the device is to be opened, the bar *g* is easily swung 85 from such closed position into the open position indicated in Fig. 2 by grasping the lip or handle *w* at the lower end of the bar *g*, and swinging said bar outward as far as the slot *u* will allow, resisting the frictional pressure 90 of the protuberance *o*. In this open position the leaves *s* are of course easily removed and others easily applied.

When the device is closed, the end of the lowest notch *q* abuts against the lip *l*, allow- 95 ing the advancing edge of the swinging bar to reach the farther edge of the stationary bar, so that the bar *g* completely covers the bar *d*. The lip *m* is longer and extends fur- 100 ther toward the right edge of the bar *d* than the lip *l*, and the highest lip *n* is longer still, whereby when the bar *g* is closing the lips *n* and *m* successively pass the advancing edge of said bar, (instead of the edge reaching both lips at the same time), and successively 105 overlap the ends of the notches *t* and *r*, thus reducing the possibility of the bar *g* becoming bent or buckling.

Having thus fully described my invention, what I claim, and desire to secure by Let- 110 ters Patent, is:-

In a loose-leaf binder adapted to be ap-

plied to a cover having ordinary sides and a connecting back, a stationary bar or member adapted to be rigidly secured to said back, leaf-receiving posts mounted on said 5 bar or member, a swinging bar or member pivotally connected at one end with the corresponding end of the stationary bar or member and provided with opposite leaf-receiving posts and with notches on its inner 10 edge, said swinging bar moving on a plane which is parallel with the surface of the stationary bar, and lips on the stationary bar facing and registering with the said notches, the lip opposite the notch which is

nearest the pivotal connection of the bars 15 being longer and extending nearer to the inner edge of the stationary bar than the lip which is at a greater distance from said pivotal connection, whereby said lips will successively overlap the swinging bar at the ends 20 of the notches, for the purpose set forth.

In testimony whereof I have signed my name to this specification in the presence of two subscribing witnesses.

JOHN E. MACLACHLAN.
